JAMES M. COMINS, OF NEW YORK, N. Y.

Letters Patent No. 106,124, dated August 9, 1870.

RAILROAD-CAR STOVE.

The Schedule referred to in these Letters Patent and making part of the same

To all persons to whom these presents may come:

Be it known that I, JAMES M. COMINS, M. D., of the city, county, and State of New York, have invented a new and useful Apparatus for Heating and Ventilating a Railway-Carriage; and do hereby declare the same to be fully described in the following specification, and represented in the accompanying drawing, of which--

Figure 1 denotes a longitudinal section.

Figure 2, a side elevation; and

Figure 3, a transverse section of the said apparatus. In such drawing--

A denotes the fire-place or chamber for combustion of the fuel, it being provided with a grate, B, and also with an ash-chamber, C, beneath such grate.

A fuel-supply hopper or reservoir, D, is arranged over the chamber A, such reservoir being furnished with an opening, a, in its top, having a door, b, hinged to it.

There extends up from the lower end, or part of the hopper or fuel-reservoir D, a hollow cylinder, e, which is closed at top, open at bottom, and furnished with a series of educts or openings, d, arranged in its sides.

Within this cylinder is a weighted conical valve, e, fixed to a stem, f, which extends up through the fuel reservoir. Furthermore, there is arranged within the fuel-holder D, so as to project from its sides, a series of arms or projections, g, whose purpose is to prevent the too ready discharge of fuel from the holder D, while the valve may be raised, and the railway carriage containing the apparatus may be in motion.

There is a flue-space, F, surrounding the fuel-holder D, and furnished with an escape-pipe, G, leading from it, in manner as represented. This flue-space is over the chamber of combustion, and separated therefrom by the top b' of the latter, through which is an opening, c', provided with a damper or valve, d'.

In respect to the grate of the fire-place, it is shown more particularly in top view in fig. 4, with its bars h closed, or in position for enabling wood to be used as fuel in it.

Each of such bars is pivoted at its opposite ends in a frame, i, the pivots k being disposed at the upper corners of the bar, or eccentrically, in manner as represented in Figure 5, which is a side view of one of the grate-bars.

Figure 6 is an end view of such bar. In other words, the pivots are disposed aside of the axis of the bar; in consequence of which the bar may be arranged to stand so that its flat side may be either vertical, or nearly so, or horizontal, or nearly so.

The bars, when turned up into horizontal positions, as they may be by running a rod, l, through the apparatus, and against them, such rod then being arranged, as shown in fig. 3, adapt the grate for the burning of

wood in the chamber of combustion, but, when the rod is withdrawn, so as to allow the gravitating grate-bars to fall into vertical positions, the spaces between them will be enlarged, and the grate be in a condition for the burning of coal in the chamber A.

There are to be openings, m n, to the fire-place and ash-chambers, such openings being furnished with doors, o p.

Immediately underneath the ash-chamber is another chamber, H, semicircular, or thereabout, in transverse section. Extending across the chamber H, at a short distance from its rear end, is a partition, g, having a hollow cone, r, projecting backward from it, in manner as represented. The partition is perforated with numerous holes, s.

A narrow flue-space, I, extends underneath the bottom of the chamber H, and up against the sides of the fire and ash-chambers, and opens at top into the chamber of combustion by a series of openings, t, made through one side of the latter, and arranged in manner as shown in fig. 3.

The flue-space I, at its opposite end, also opens into the flue-space F. At its rear end the chamber H opens into a vertical air-supply pipe or conductor, K, whose lower part opens through the floor of the railway carriage, and is provided with a damper or valve, u, the whole being as represented.

The air-conduit is to extend through the roof, and above the top of the railway carriage, and is to be surmounted by a hood, L, which is to be open at its opposite ends, and furnished with a partition, v, arranged at its middle, in manner as shown, the same being so as to cause air to be blown into the conduit in whichever direction the railway carriage at any time may be in movement on the railway track.

The air-supply flue may have, near its lower end, a hole in its side, such hole to be furnished with a closing slide, w, and being for the purpose of letting cool air into the carriage or space about the heating and ventilating apparatus, as occasion may require, in order to modify or lessen the temperature of the air in the carriage.

From the front end of the chamber H a pipe or conduit, L', leads into an evaporating vessel, M, to contain water, such vessel having a foraminous partition, x, extended across it above the water-space.

This partition is to prevent the water from being swashed up into the chamber H, or an air-conduit, N, while the carriage may be in motion.

The said air-conduit N is to lead out of the evaporating vessel, and along underneath the several seats of the railway carriage, and should have air-vents or openings to supply the warmed air to the parts contiguous to the seats.

Guard-flues, O O, are arranged against the outer

sides of the flue-spaces I, these flues O O being open at or near their tops, as shown at y, and at their bottoms, as shown at z, where they lead into a hollow base, P, provided with openings, a', through its sides, and composing part of the apparatus.

The operation of the apparatus above explained may be thus explained.

While the railway carriage is in motion, air will be caused to enter the supply-pipe K; such air will be forced down the pipe, and into the air-heating chamber H, and will impinge against its cone r, and, by it, will be directed toward the perforations of the partition g. The air will flow through the openings of such partition, and, by reason of the hollow cone, it will be more or less retarded in its flow through the chamber H, in which it will be heated by the heat that may be radiated from its sides. From the chamber H the air so heated will escape by the conduits leading into and from the evaporating vessel M.

The smoke and volatile products of combustion of the fuel in the fire-place will pass therewith into the flue-space I, on one side of the fire-place, thence down such, and underneath and around the air-heating chamber H, thence up the flue-space I, in the opposite side of the fire-place, and from thence into the space F, and, finally, into the smoke-discharge flue leading therefrom.

The apparatus may be employed to great advantage in heating and ventilating railway carriages, dwellings, or other structures.

I claim—

The arrangement and combination of the open hoods or bonnets I, made and provided with a partition, r,

as described, the air-duct K, the air-heating chamber H, the perforated partition g, and the cone r, with the ash and fire-chambers A C disposed as specified.

Also, the combination and arrangement of the cone r, and perforated partition g, with the air-heating chamber H arranged under the ash-chamber C, as set forth.

Also, the fuel-supply reservoir D, as provided with the series of arms or prongs, y, for the purpose specified.

Also, the fuel-supply reservoir D, as made or provided with the hollow cylinder e, and the discharge-openings d, and valve e, arranged as described.

Also, the arrangement of the evaporating vessel M, and its air-conduits, with the air-heating chamber disposed beneath the ash-chamber, and provided with an air-supplying apparatus, as set forth.

Also, the air-heating and ventilating apparatus constructed substantially in manner and so as to operate as described, and consisting of the chamber of combustion A, the ash-chamber C, the fuel-supply reservoir D, the flue-space F, around the latter the flue-space, I, and air-heating chamber H, the guard-flues O O, the hollow base P, the air-supply conduit K, and its bonnet or hood L, as explained, such being provided with one or more ducts for the distribution of the heated air, as set forth.

J. M. COMINS, M. D.
